FOLDING CARTON

Ray W. Marshall, Rittman, Ohio, assignor to The Ohio Boxboard Company, Rittman, Ohio, a corporation of Ohio

Application July 9, 1940, Serial No. 344,567

4 Claims. (Cl. 229—33)

In so-called "infold cartons," that is to say, cartons of boxboard, cardboard, or other paperboard or similar appropriate material, made from cut, scored and folded blanks so formed that their cooperative parts may be pasted or otherwise joined while in folded condition, it has been found that when these cartons as ordinarily constructed are set up for use they have a marked tendency to reassume their folded condition due to the inherent spring in the material, and the walls of the cartons therefore are what is known in the trade as "soft" and lack that rigidity which is desirable.

One object of the present invention is to overcome this objection of "softness" by providing means for relatively rigidly supporting the walls in set-up condition, such means forming an integral part of the carton blank and functioning automatically when the carton is adjusted to set-up condition.

Another object of the invention is to form the carton in such manner that the customary diagonal fold lines of opposite walls, usually the end walls, upon which these walls are folded to accomplish the pasting operation, may be at 45° to the lines of fold between the walls and bottom of the carton, so that when the carton is adjusted to set-up condition the walls will assume positions perpendicular to the bottom.

The invention contemplates a folding carton having a body including a bottom, side walls and end walls constituting parts of an integral blank and defined by cuts and scores upon which latter the walls are folded relatively to the bottom, certain of said walls, preferably the end walls, comprising outer members connected with the bottom and inner members constituting flaps attached to the adjacent side wall, the outer members being foldable upon diagonal score lines and the flaps being attached to the outer free triangular portions defined by such diagonal score lines, said flaps having their edges which are normally adjacent to the bottom provided with means which, when the carton is adjusted to set-up condition will engage the bottom to frictionally retain the walls perpendicular to the bottom, the body being apertured adjacent to the line of fold between the flap-carrying side wall and the bottom so that said means will be accommodated when the carton is in folded condition, all as will be explained hereinafter more fully and finally claimed.

In the accompanying drawings illustrating the invention, in the several figures of which like parts are similarly designated;

Figure 1 is a plan view of the carton blank in flat condition.

Fig. 2 illustrates the carton blank after the first folds preliminary to pasting have been made.

Fig. 3 illustrates the blank fully folded and pasted.

Fig. 4 is a perspective view showing the carton in partially set-up condition.

Fig. 5 is an enlarged perspective view of the carton in completely set-up condition, and closed.

Fig. 6 is a fragmentary sectional perspective view taken substantially on the line *a—b*, Fig. 5, and looking into one end of the set-up and closed carton, and

Fig. 7 is a sectional elevation taken on the line *a—b*, Fig. 5, and looking into the end thereof.

The carton illustrated in the drawings is of the window type ordinarily used for packaging cake, bread and similar food products, and may, as above stated, be made from a blank of suitable box board, cardboard or other paperboard or appropriate material, such blank being suitably cut and scored to define a bottom 1, side walls 2 and 3, end wall members 4 and a top 5, the side wall 3 and top 5 being provided with a continuous window opening 6.

The front wall 2 carries at its ends integral flaps 7 separated from the end wall members 4 by cuts 8 extending in substantial alignment with the score or fold line 9 between the bottom 1 and side wall 2, though slightly offset outwardly therefrom. These cuts 8 are so formed as to provide friction means 10, preferably in the form of feet, upon the edges of the flaps 7 which ultimately stand adjacent to the bottom 1 when the carton is in set-up condition, and it will be noted that although the cuts 8 are offset outwardly from alignment with the score or fold line 9, they are not thus offset to an extent equal to the distance at which the feet offstand from the edges of the flaps. It will thus be apparent that when the blank is in completely folded condition, as shown in Fig. 3, the feet 10 must extend outwardly past the line of fold 9, and provision for the accommodation and passage of the feet is made by forming partially severed tongues 11 preferably in the bottom 1 and having their free edges lying in the score or fold line 9 to furnish appropriate apertures.

The end wall members 4 are provided with diagonal scores or fold lines 12 extending from relief openings 13 arranged at the junction of the score or fold line 9, the cuts 8 and scores or fold lines 14 and 15, upon which latter the end wall members 4 and flaps 7, respectively, are folded

relatively to the bottom 1 and side wall 2, and these scores or fold lines 12 provide for folding of the members 4 for pasting and are arranged at an angle of 45° to the score or fold line 9 for a purpose hereinafter appearing.

Attached to the end wall members 4 are opposite side wall elements 16 foldable with respect to the members 4 upon scores or fold lines 17, and these side wall elements 16 are severed from the side wall 3 by cuts 18.

The side wall 3 is foldable with respect to the bottom 1 upon a score or fold line 19.

The top 5 is foldable with relation to the side wall 3 upon a discontinuous score or fold line 20, and this top carries side and end skirt-forming members 21 and 22, respectively, foldable relatively to the top 5 upon scores or fold lines 23 and 24, respectively. The skirt member 21 is provided with pasting tabs 25 at its opposite ends, and these tabs are foldable upon scores or fold lines 26 and cooperate with and are pasted, as will be described, to the outer corners 27 of the skirt members 22, which corners are foldable upon diagonal scores or fold lines 28 preferably arranged at an angle of 45° to the score or fold line 23.

The skirt member 21 and the side wall 2 are provided, respectively, with tongue and slot means 29 and 30 which, when engaged, as illustrated in Fig. 5, serve to hold the cover closed upon the carton.

The window opening 6 may, if desired, be provided with a panel or closure of Cellophane or other transparent material (not shown) as is customary in cartons of this general nature.

Aside from the feature of the feet 10 and the cooperating aperture-forming tongues 11, the blank of this infold carton is folded for pasting to assembled form in substantially the same manner as infold cartons of known types, such folding and pasting usually being performed upon automatic machines provided for the purpose. Referring particularly to Figs. 1 and 2, it will be seen that the first folds of the carton elements are accomplished by folding the parts 1, 4, 16, 22 and 25 inwardly upon their respective scores or fold lines 15, 14, 24 and 26, over the parts 2, 1, 3, 5 and 21, and then the end wall members 4 and skirt members 22 have their free corners 31 and 27, respectively, folded outwardly upon their diagonal scores or fold lines 12 and 28, (Fig. 2), thus presenting exposed triangular surfaces to which paste is applied. With the blank thus folded and prepared for pasting, the side wall 2 with its flaps 7 is folded inwardly over the bottom 1 and over the free corners 31 of the end wall members 4, and the skirt member 21, with its tabs 25, is inwardly folded over the top 5 and over the free corners 27 of the skirt members 22, all as shown in Fig. 3, and pressure is applied over the whole folded blank to cause adhesion and complete the pasting operation.

It is to be noted that when the side wall 2 with its folded flaps 7 is inwardly folded as last described, the feet 10 of the flaps 7 will depress the tongues 11 and pass outwardly through the apertures thus provided, thereby preventing any distortion of the folded carton due to the off-standing nature of the feet 10.

To set up the carton, the parts will be unfolded and distended, as shown in Fig. 4, and by a suitable outward pressure exerted upon the side wall 2 and the flaps 7, the feet 10, undistorted, and remaining in the plane of the flaps 7, will be caused to slide laterally over the bottom in

such frictional engagement therewith that when the side wall members 4 are fully flattened, as indicated in Figs. 5, 6 and 7, the side wall 2 and the end walls will be restrained from springing back to folded condition and they and the corners joining them will be held rigidly erect. Moreover, due to the angle of 45° at which the scores or fold lines 12 are arranged, the side wall 2 and the end walls will be supported perpendicular to the bottom 1.

The carton is now ready to receive the merchandise to be packaged, and closing of the carton is accomplished by turning inwardly upon the scores or fold lines 17 the side wall elements 16, suitably erecting the skirt-forming members 21 and 22 of the top 5, and upwardly folding the side wall 3 upon the score or fold line 19 into contact with the side wall elements 16, and then closing the top 5 down upon the side wall 2 and end walls 4 by folding it upon the discontinuous score or fold line 20, and engaging the tongue and slot means 29, 30, as illustrated in Fig. 5.

It will be apparent that the end walls of the carton comprise the outer members 4 including the triangular portions 31, and inner members formed by the flaps 7 which are pasted to the triangular portions 31, and inasmuch as those portions of the flaps 7 which do not overlie, and hence are not pasted to, the triangular portions 31, are free for movement relatively to the outer members 4, they may be appropriately adjusted with respect to the bottom 1 as the carton is distended to set-up condition as hereinbefore described. Moreover, if desired, the carton may be re-collapsed to folded condition by swinging the free portions of the flaps 7 away from the end wall members 4, as will be apparent.

Various changes and modifications are considered to be within the spirit of the invention and the scope of the following claims. For example, although, in the form shown, the flaps 7 bearing the friction means or feet 10 form parts of the end walls, they might equally well form parts of a side wall, in which case the aperture-forming tongues 11 would be located adjacent to the scores or fold lines between the bottom and the end walls. Also, the invention might be adapted to cartons of types other than that particularly shown and described wherein a relatively rigid construction and properly erected set-up condition are desired.

What I claim is:

1. In a folding carton, a body including a side wall, an end wall and a bottom interconnected and relatively foldable upon predetermined lines of fold, one of said walls including a flap secured to it and integral with the other wall, said flap having an edge normally in substantial alignment with the line of fold between its integral wall and the bottom, said one wall being provided with inner and outer triangular portions defined by a diagonal line of fold at 45° to the line of fold between said other wall and the bottom, and said flap being attached to said outer triangular portion whereby when the carton is in set-up condition the walls will be perpendicular to the bottom, and a foot on said flap offstanding from said edge and hence extending beyond the line of fold between its integral wall and the bottom, said foot being frictionally engageable with the bottom to maintain said walls erect when the carton is set up.

2. In a folding carton, a body including a side wall, an end wall and a bottom interconnected and relatively foldable upon predetermined lines

of fold, one of said walls including a flap secured to it and integral with the other wall, said flap having an edge normally in substantial alignment with the line of fold between its integral wall and the bottom, said one wall being provided with inner and outer triangular portions defined by a diagonal line of fold at 45° to the line of fold between said other wall and the bottom, and said flap being attached to said outer triangular portion whereby when the carton is in set-up condition the walls will be perpendicular to the bottom, and a foot on said flap offstanding from said edge and hence extending beyond the line of fold between its integral wall and the bottom, said foot being frictionally engageable with the bottom to maintain said walls erect when the carton is set up, said body being apertured adjacent to said line of fold between the bottom and the said other wall to accommodate said foot when the carton is in folded condition.

3. In a blank for a folding carton, three walls connected to form a carton corner, two of said walls being foldable relatively to the third wall upon predetermined lines of fold and one of said foldable walls including a member hinged thereto and adapted to be secured throughout a portion of its area to the other foldable wall, said hinged member being thereby partially movable with respect to the wall to which it is secured when the carton is adjusted to flat folded condition, and said hinged member having one edge normally in substantial alignment with the line of fold of the wall of which it forms a part and provided with means cut from the portion of the

other wall to which it is adapted to be secured and offstanding from said edge to an extent beyond said line of fold and serving to frictionally engage said third wall when the carton is in set-up condition to thereby maintain the corner erect, said offstanding means being undistorted and lying in the plane of the hinged member throughout use of the carton.

4. In a blank for a folding carton, three walls connected to form a carton corner, two of said walls being foldable relatively to the third wall upon predetermined lines of fold and one of said foldable walls including a member hinged thereto and adapted to be secured throughout a portion of its area to the other foldable wall, said hinged member being thereby partially movable with respect to the wall to which it is secured when the carton is adjusted to flat-folded condition, and said hinged member having one edge normally in substantial alignment with the line of fold of the wall of which it forms a part and provided with means cut from the portion of the other wall to which it is adapted to be secured and offstanding from said edge to an extent beyond said line of fold and serving to frictionally engage said third wall when the carton is in set-up condition to thereby maintain the corner erect, said offstanding means being undistorted and lying in the plane of the hinged member throughout use of the carton, and an aperture at said line of fold to accommodate said frictional engaging means when the carton is in folded condition.

RAY W. MARSHALL.
